(57) **CLAIM**

The ornamental design for a capsule for dispensing flowable 3D printing medium, as shown and described.

DESCRIPTION

FIG. 1 is an isometric view of a capsule for dispensing flowable 3D printing medium showing a first embodiment of our new design.

FIG. 2 is a front elevational view of the capsule for dispensing flowable 3D printing medium thereof, the real, left side, and right side elevational views being identical thereto. FIG. 3 is a top plan view of the capsule for dispensing flowable 3D printing medium thereof.

FIG. 4 is a bottom plan view of the capsule for dispensing flowable 3D printing medium thereof.

FIG. 5 is an isometric view of a capsule for dispensing flowable 3D printing medium showing a second embodiment of our new design.

FIG. 6 is a front elevational view of the capsule for dispensing flowable 3D printing medium thereof, the real, left side, and right side elevational views being identical thereto. FIG. 7 is a top plan view of the capsule for dispensing flowable 3D printing medium thereof; and,

FIG. 8 is a bottom plan view of the capsule for dispensing flowable 3D printing medium thereof.

The portions of the capsule for dispensing flowable 3D printing medium shown in broken lines form no part of the claimed design.

1 Claim, 2 Drawing Sheets
